UNITED STATES PATENT OFFICE.

THOMAS CANDY, OF CINCINNATI, OHIO.

DESIGN FOR A BOX.

SPECIFICATION forming part of Design No. 13,692, dated March 6, 1883.

Application filed December 29, 1881. Term of patent 7 years.

To all whom it may concern:

Be it known that I, THOMAS CANDY, of Cincinnati, Hamilton county, Ohio, have invented a new and useful Design for a Box, of which 5 the following is a specification.

In the accompanying drawings, Figures 1 and 2 are respectively an obverse and a reverse perspective view of my design. Fig. 3 is an axial section.

10 The box is of circular contour, of flattened oval form in its axial section. Each side or face of the box has an annular bead or fillet, *a*, constituting the inclosing frame or border of a slightly-crowning panel, *b*. This panel *b* on the obverse side is ornamented with a rilievo, *c*, representing a jockey riding a horse at a full run on a stretch or straight section, *f*, of a race-track. Below the representation of the jockey, running horse, and stretch of 15 the track there is generally placed the inscription *d* of the words "On Time." The reverse panel *b'* has the representation *e*, *in rilievo*, of the hours and hands of a watch. Extend-

ing from one edge of the said box is a perforated lug in semblance of a watch-*pendant*. 25

I claim as a new and original design for a box—

1. The design for a box, consisting of a running horse and jockey and stretch of track, displayed to occupy the central field of the 30 box, and inclosed by a circular border, substantially as shown and described.

2. The design for a box, consisting of the representation of the hours and hands of a watch on one side of the box, the representation 35 of a watch-*pendant* at one edge thereof, and the representation of a running horse, jockey, and stretch of track on the other side of the box, substantially as shown and described.

In testimony of which invention I hereunto 40 set my hand.

THOMAS CANDY.
